I. M. PEASE

TRUSS

Filed June 4, 1923

Isaac M. Pease,
Inventor.

UNITED STATES PATENT OFFICE.

ISAAC M. PEASE, OF CINCINNATI, OHIO.

TRUSS.

Application filed June 4, 1923. Serial No. 643,318.

To all whom it may concern:

Be it known that I, ISAAC M. PEASE, a citizen of the United States, residing at Cincinnati, in the county of Hamilton and 5 State of Ohio, have invented a new and useful Truss, of which the following is a specification.

This invention aims to provide a novel means whereby the rear ends of a body-encircling truss spring may be assembled 10 slidably with the back pads, thereby enabling the ends of the spring to work upon the pads when the wearer stoops, bends or assumes any other unusual posture, it being 15 possible to hold the pads fixed, at the will of the wearer.

It is within the province of the disclosure to improve generally and to enhance the utility of devices of that type to which the 20 invention appertains.

With the above and other objects in view, which will appear as the description proceeds, the invention resides in the combination and arrangement of parts and in the 25 details of construction hereinafter described and claimed, it being understood that, within the scope of what is claimed, changes in the precise embodiment of the invention shown can be made without departing from 30 the spirit of the invention.

In the accompanying drawings:

Figure 1 shows in elevation, the rear end of a body-encircling truss spring, having devices constructed in accordance with the 35 invention; Figure 2 is a section on the line 2—2 of Figure 1; Figure 3 is a section on the line 3—3 of Figure 1.

The numerals 1 and 2 denote the ends of a body-encircling truss spring. The securing element 3 holds a link 4 on the end 1, the link carrying one end of a longitudinally extensible strap 5, provided with a slit 6 whereby the strap may be assembled with a securing element on the end 2, the 45 securing element being constructed like the securing element 3. For convenience in claiming the invention the link 4 and the strap 5 may be alluded to generally as a connection. The securing elements 3 and 50 7 project beyond the inner surface of the ends 1 and 2 of the truss spring, as denoted by the numeral 8 in Figure 3.

Slides 9 are mounted for reciprocation on the ends 1 and 2 of the truss spring longitudinally of the said ends, the slides having

flanges 10 which overhang the ends 1 and 2 of the truss spring, longitudinally of the said ends, as clearly shown in Figure 2. The movement of the slides 9 inwardly, that is toward each other is limited by the 60 ends 8 of the securing elements 3 and 7, outward movement of the slides, in opposite directions being limited by the ends of the covering 11 wherewith the truss spring is surrounded, this covering being made of 65 hard rubber or any other suitable material. Back pads 12 of any desired construction are attached as at 14 in any suitable way to the slides 9, the swiveled connection shown in Figure 2 being resorted to if considered 70 expedient.

In practical operation, the slides 9 are set approximately in the positions shown in connection with the slide at the right hand end of Figure 1, the result being that when 75 the wearer stoops, bends, or assumes any other unusual posture, the ends 1 and 2 of the truss spring will reciprocate in the slides 9, the back pads 12 remaining in place in contact with the body of the wearer. 80

It is to be understood that the pad may be of any desired kind either hard rubber celluloid, leather covered, rubber covered, or of any other form. The back pad is disposed close to the spring and lies almost flat 85 against the spring.

What is claimed is:

1. A device of the class described comprising a truss spring, a slide mounted for reciprocation on one end of the spring, separate means carried by the spring for limiting the movement of the slide in opposite directions, one of said means being removable, a pad carried by the slide, and means assembled with the slide for holding the 95 slide against movement at any position between the limits of its movement.

2. In a device of the class described, a truss spring, studs carried by the truss spring, slides mounted on the truss spring, the studs constituting means for limiting the movement of the slides toward each other, means on the truss spring for limiting the sliding movement of the slides away from each other, a link mounted pivotally 100 on one stud, and a connecting element assembled with the link and engaged with the other stud and pads fastened to the slides. 105

3. In a device of the class described, a truss spring, a slide mounted to reciprocate 110

on one end of the truss spring, a stud on said end of the truss spring, a link carried by the stud, a connection assembled with the link, means for uniting the connection detachably with the other end of the truss spring, a slide mounted to reciprocate on the first specified end of the truss spring and limited in its sliding movement, in one direction, by the stud, means for limiting the sliding movement of the slide in an op-

posite direction, and a pad carried by the slide.

In testimony that I claim the foregoing as my own, I have hereto affixed my signature in the presence of two witnesses.

ISAAC M. PEASE.
